UNITED STATES PATENT OFFICE

ARTHUR R. SMITH, OF SCHENECTADY, NEW YORK, ASSIGNOR TO GENERAL ELECTRIC COMPANY, A CORPORATION OF NEW YORK

STEAM CONDENSER

Application filed December 10, 1927. Serial No. 239,044.

The present invention relates to steam condensers of the tube type such as are used in power plants for condensing the exhaust from a steam engine or engines. In connection with the use of such condensers, as is well known, the cooling water is passed through the tubes and the exhaust steam is passed over the outside of the tubes and condensed. The condensate is used for feeding the boilers since it represents a source of supply of pure water and its use for this purpose is important in the operation of a power plant. For cooling water any available supply is utilized. Often the cooling water is impure and not fit for use in boilers, for example, in some instances salt water is utilized. Where impure cooling water, such as salt water for example, is used in the condenser, it is important that no leakage of impure water into the condensate should take place. However, in actual practice this is a thing difficult to prevent as often one or more tubes of the condenser may develop a leak due to becoming corroded, pitted, or cracked, for example.

The object of my invention is to provide an improved condenser construction wherein if rupture occurs in a condenser tube the leakage will be of condensate or steam into the cooling water rather than that of cooling water into the condensate. As a result, therefore, in an apparatus embodying my invention, there cannot occur contamination of the condensate by the cooling water.

For a consideration of what I believe to be novel and my invention, attention is directed to the accompanying description and the claims appended thereto.

In the drawing, Fig. 1 is a sectional view partly diagrammatic, of a tube condenser embodying my invention; Fig. 2 is a detail, sectional view of a pressure control valve; Fig. 2^a is a detail view on a larger scale showing the way the tubes in Fig. 1 are connected into the tube sheets; Fig. 3 is a vertical sectional view of a modified form of my invention; Fig. 4 is a detail view illustrating the operation of the modification shown in Fig. 3, and Fig. 5 is a detail, sectional view taken on line 5—5, Fig. 3.

Referring to the drawing, Figs. 1 and 2, 1 indicates the condenser shell, 2 and 3 the heads, and 4 the opening in the shell through which exhaust steam enters. At opposite ends of shell 1 are tube plates 5 and 6 in which are mounted the condenser tubes 7. 8 is a partition plate dividing the chamber at the right-hand end of the condenser shell into two parts. The inlet conduit for cooling water is indicated at 9 and the discharge conduit at 10. The cooling water enters through conduit 9, flows through the tubes 7 connected to tube plate 6 below partition plate 8 to the left hand end of the condenser shell, then back through the tubes connected with tube plate 6 above partition plate 8 and out through conduit 10. 11 indicates a well in which the condensate collects and from which it is pumped by a pump 12 to a discharge pipe 13 which may lead to a hot well from which the boilers are supplied, or directly back to the boilers of the plant.

The condenser structure so far described is a known one and is to be taken as illustrating any suitable type of tube condenser.

According to the modification of my invention shown in Figs. 1 and 2, I provide in spaced relation to tube plates 5 and 6, additional tube plates 14 and 15 into which are connected tubes 16, the tubes 16 surrounding the condenser tubes 7 in spaced relation thereto to provide annular spaces 17. At their right hand ends the annular spaces 17 communicate with a chamber 18 which is formed between tube plates 6 and 15 and at their left hand ends they communicate with a chamber 19 which is formed between tube plates 5 and 14. 20 indicates a suitable pump having its suction conduit 21 connected to chamber 19 and its discharge conduit 22 connected to chamber 18. Pump 20 may be driven in any suitable manner. For example, it may be driven by an electric motor (not shown). Pump 20 is thus adapted to circulate water continuously through the annular spaces 17, there being provided a closed circuit for the pump.

The arrangement is such that pump 20 will maintain the water which it is circulating at a pressure higher than the pressure of the

cooling water in tubes 7. As a result, therefore, the condenser tubes 7 are surrounded by water of a pressure greater than that of the cooling water in the tubes. Any leakage which occurs, therefore, will be that of water from annular spaces 17 into the condenser tubes 7 and not from the condenser tubes out into spaces 17.

Any suitable supply of pure water may be utilized for circulation through the annular passages 17. I may with advantage employ condensate from the condenser and this arrangement is illustrated in the drawing. To this end, the suction conduit 21 of pump 15 20 is connected to the discharge conduit 13 of the pump 12 by a feed pipe 23. Preferably, I provide in feed pipe 23 a control valve which operates automatically to maintain the closed circulating system sufficiently 25 full of water to maintain the pressure therein. The control valve is illustrated in section in Fig. 2. It comprises valve casing 24 in which is a valve 25 having its stem 26 connected to a flexible diaphragm 27 arranged in a casing 28. The underside of diaphragm 27 is connected by a pipe 29 to suction conduit 21 and the upper side of diaphragm 27 is connected by a pipe 30 to the chamber formed at the left hand end of condenser shell 1 by tube plate 5. 31 is a spring which tends to open valve 25. When valve 25 is opened water is fed through pipe 23 to suction conduit 21 of the closed circulating system. As long as the pressure in the closed 35 system is a predetermined amount higher than the pressure in the cooling water system, diaphragm 27 holds valve 25 closed. In case, however, the difference in pressure decreases below the predetermined amount, a 40 thing which may occur due to water leaking from the closed system thereby lowering the pressure therein, then spring 31 serves to open valve 25 thereby admitting additional water to the closed system so as to maintain 45 the closed system filled and the pressure therein at the desired high value. In this connection, it will be understood that the pressure on the discharge side of pump 12 is higher than the pressure in inlet conduit 50 21.

Fig. 2^a shows the manner in which the concentric tubes 7 and 16 are connected to the tube plates whereby the tubes may be removed and replaced without removing the 55 outside tube plates. The tube plates 5 and 6 are provided with openings large enough for tubes 16 to pass through them and tubes 7 are expanded somewhat at their ends and are packed and centered in said openings 60 by suitable packing means such as is indicated at 7^a. Tubes 16 fit the openings in tube plates 14 and 15 and are provided with suitable packing means such as is indicated at 16^a. With this arrangement, it will be 65 seen that by removing packing means 7^a a

tube 7 may be withdrawn and that then the outer tube 16 may be withdrawn through the corresponding opening in the tube plates 5 or 6.

With the foregoing arrangement, it will be seen that automatically I maintain around each condenser tube a pressure higher than that within the tube, so that, as already pointed out, any leakage will be into the condenser tube and not out from the condenser tube. Also it will be seen that I provide means which automatically maintains the closed circulating system full of water so as to take care of leakage from the closed system.

In the operation of the condenser, the heat from the steam to be condensed is transferred to the cooling water through the intermediary of the pure water in the annular spaces 17.

In Figs. 3, 4 and 5, I have shown a modified form of my invention wherein instead of surrounding the condenser tubes by separate tubes in order to maintain on the outside of the tubes a pressure higher than that within them, I provide a means whereby the pressure within the tubes is maintained lower than or the same as that which exists in the condenser in the region surrounding the tubes. By this means, it will be seen that I accomplish the same result as is accomplished in the construction shown in Figs. 1 and 2 in that any leakage will be of steam or condensate into the tubes and not of cooling water from the tubes; or if balanced pressures exist, no flow in either direction.

In Figs. 3, 4 and 5, 40 indicates the shell of a vertical tube condenser, 41 and 42 indicate the upper and lower tube plates, 43 indicates the tubes, and 44 indicates the opening through which exhaust steam enters the condenser. At 45 is indicated a pipe through which condensate is withdrawn from the condenser shell and at 45^a is indicated an air pump connection through which air is withdrawn from the condenser shell. At the upper end of the condenser is a head 46 having an inlet conduit 47 through which cooling water is supplied to the condenser. Head 46 is provided with several distributing passages 48 which communicate with inlet conduit 47 and serve to distribute cooling water entirely over the tube plate 41 so that water reaches all the tubes. Also, I may provide baffles 49 in the head 46 between the rows of tubes to assist in maintaining a more constant head of water on each tube. Such baffles are especially useful in case the condenser is used on shipboard as they will then serve to maintain a more constant head on each tube regardless of the roll of the ship.

Connected to inlet conduit 47 is a pipe 50 through which cooling water is supplied from any suitable source, the pipe being provided with a regulating valve 51 for regulating the cooling water supply as is usual. Also, connected to head 46 is an air pump connection 55

52 through which air is withdrawn from the head.

At the lower end of the condenser are walls forming a chamber 53 in which is located a pump 54. The suction inlet 55 of pump 54 communicates with chamber 53 and the discharge pipe 56 passes out through a wall of chamber 53 and may lead to any suitable discharge region.

The operation of the construction shown in Figs. 3 to 5 is similar to that of a combination surface and jet condenser. Pump 54 operates to remove the cooling water from chamber 53 and along with the air pump connected to pipe 52 to maintain in chamber 53 and the space within the tubes 43 a vacuum as low as or lower than that in the space surrounding tubes 43. Pipe 50 is connected to a source of cooling water supply, the cooling water being drawn up through the pipe to head 46 by the vacuum. Valve 51 is adjusted to regulate the volume of the cooling water supply so as to maintain such a head of water as will produce an initial velocity lower than the velocity which will be obtained due to gravity. With this arrangement, the water in the top of the tubes will be solid and as the velocity speeds up due to the water falling by gravity down the tubes, air cores will be formed at the centers of the tubes and the cooling water will flow along the sides of the tubes to chamber 53. This is illustrated in Fig. 4 where 58 indicates the water at the tops of the tubes, 59 indicates the air cores and 60 indicates the water flowing along the sides of the tubes.

It is desirable that chamber 53 be connected to head 46 so that the vacua are equal. This may be accomplished by the air cores or I may provide a separate air connection, a thing which may be done by extending one or more of the tubes 43 above the level of the liquid in head 46 as is indicated at 61. While I have referred to the cores 59 as being air cores, it will be understood, of course, that actually but little air is present because of the high vacuum existing.

Since the pressure in tubes 43 is lower than the pressure in the region surrounding the tubes, any leakage will be exhaust steam or condensate into tubes 43 and not leakage from tubes 43 into the condensate.

In accordance with the provisions of the patent statutes, I have described the principle of operation of my invention, together with the apparatus I now consider to represent the best embodiment thereof, but I desire to have it understood that the apparatus shown is only illustrative and that the invention may be carried out by other means.

What I claim as new and desire to secure by Letters Patent of the United States, is:

1. The combination with a surface condenser comprising means forming passages for the flow of cooling water, of means where-

by there is maintained around said passage-forming means throughout their length a pressure higher than that within such passages whereby any leakage will be into the cooling water passages.

2. The combination with a surface condenser comprising tubes through which cooling water flows, of means whereby the pressure in the region surrounding said tubes is maintained throughout the length of said tubes at a value higher than the pressure within the tubes.

3. The combination with a surface condenser comprising tubes through which cooling water flows, of means defining passages surrounding said tubes throughout their length, and means for maintaining in said passages a pressure higher than that within the tubes.

4. The combination with a surface condenser comprising tubes through which cooling water flows, of means defining passages surrounding said tubes throughout their length, and means for circulating continuously through said passages a fluid under a pressure higher than the pressure within the tubes.

5. The combination with a surface condenser comprising tubes through which cooling water flows, of means defining passages surrounding said tubes throughout their length, and a closed circulating system connected to said passages, said circulating system including pump means for maintaining in the system a pressure higher than that within the tubes.

6. The combination with a surface condenser comprising tubes through which cooling water flows, of means defining passages surrounding said tubes throughout their length, a closed circulating system connected to said passages, said circulating system including pump means for maintaining in the system a pressure higher than that within the tubes, and means for automatically supplying fluid to said closed system.

7. The combination with a surface condenser comprising tubes through which cooling water flows, of means defining passages surrounding said tubes throughout their length, a closed circulating system connected to said passages, said circulating system including pump means for maintaining in the system a pressure higher than that within the tubes, and means for supplying condensate from the condenser to said closed circulating system.

In witness whereof, I have hereto set my hand this 8th day of December, 1927.

ARTHUR R. SMITH.
